UNITED STATES PATENT OFFICE.

EDMUND B. BLINN, OF PASADENA, CALIFORNIA, ASSIGNOR OF ONE-THIRD TO HENRY BARKSCHAT, OF LOS ANGELES, CALIFORNIA.

CONCRETE POLE.

1,353,309.

Specification of Letters Patent. Patented Sept. 21, 1920.

Application filed October 27, 1919. Serial No. 333,546.

To all whom it may concern:

Be it known that I, EDMUND B. BLINN, a citizen of the United States, residing at Pasadena, in the county of Los Angeles, State of California, have invented new and useful Improvements in Concrete Poles, of which the following is a specification.

This invention relates to poles and particularly to poles such as are used for lamps, or for supporting wires of various kinds, for instance, telephone wires, telegraph wires, signal wires, etc. It is an object of this invention to provide a simple, sightly pole construction of this general construction by which a pole may be provided which requires no hooks or special apparatus to be employed by a person climbing it.

The invention is particularly adapted to be applied or used in connection with monolithic concrete poles and the like, although it is not limited to such application it being readily applicable to metal poles or wooden poles, etc. The invention provides steps in or on the pole so spaced and shaped that a person can easily and safely climb the pole. In the case of a concrete pole or cast metal pole the steps are formed in the concrete or metal when the pole is made and are either indentations or projections extending around the pole completely or partially as will be hereinafter explained in detail.

Vertical ribs formed by depressions or projections are provided in the pole, between the steps, which projections or depressions provide grips or hand holds for a person climbing the pole. The ribs or depressions are a particular feature of the invention as they provide convenient grips for a person and make it unnecessary for the person to wrap his arms around the pole.

The simplicity of the invention makes it possible to easily and inexpensively embody it in poles without effecting their strength or sightliness. The fact that the invention may be embodied in a pole at very little expense makes it of great commercial value.

Further objects and features of the invention will be clearly understood from the following detailed description of a preferred embodiment of the invention throughout which reference is had to the accompanying drawings, in which—

Figure 1 is a view of a typical pole embodying the invention; Fig. 2 is an enlarged

section taken as indicated by line 2—2 on Fig. 1; Fig. 3 is an enlarged section taken as the top of the pole; Fig. 4 is a view of a section or portion of pole showing a form of construction which can be used; Fig. 5 is a view similar to Fig. 4 of another form of construction; Fig. 6 is a sectional view of a portion of the pole in which the pole is formed showing the manner in which the reinforcing frame is supported; Fig. 7 is a sectional view of a pole showing a manner in which the hand holds may be formed; Fig. 8 is a view similar to Fig. 7 of another form of construction; Fig. 9 is a sectional view showing a manner in which the cross arms can be mounted on the pole; Fig. 10 is a view taken as indicated by line 10—10 on Fig. 9; and Fig. 11 is a view similar to Fig. 9 of another form of construction.

Throughout the drawings numeral 10 designates a typical pole such as is used for supporting wires of various kinds. The pole 10 extends into the ground 11 and may be anchored or supported in any ordinary manner. A cross arm 13 for carrying wires 80 may be attached to the pole near its upper end as shown in Fig. 1. The height or size of the pole makes no material difference and it will be understood that the particular pole herein shown and described is merely typical and for purpose of illustration.

The pole 10 may be made of various materials and may be in sections although it is preferred that it be monolithic concrete or metal. Concrete poles can be manufactured at very low cost and the embodying of the present invention adds practically nothing to the cost of the poles. When the pole is monolithic concrete or metal it is preferably formed in a mold. Although the invention is not limited to any particular method of forming the pole it is preferred that it be formed in a mold which is rotated so that the concrete is packed by centrifugal force and so that a hole is left through the center 100 of the pole, as illustrated in the drawings. It has been found by practice that monolithic concrete poles require or are greatly strengthened by metallic reinforcement. In the preferred form of construction I provide the pole with longitudinal reinforcing wires 16 and a coiled wire 15, as shown in the drawings. In the preferred method of construction the reinforcing wires 15 and 16 are bound together at their points of 110

intersection by wire or the like. Before the concrete is poured into the mold and before the mold is rotated the reinforcing frame, formed by the wires, is placed in the mold 5 and spaced or held in position by blocks 18 which engage the side wall 19 of the mold. The blocks 18 are concrete having embedded in them wires 20 by which the reinforcing frame is connected to them. The blocks 18 10 are so arranged in the mold as to support the reinforcing frame and prevent it from becoming displaced or disarranged by centrifugal force when the mold is being rotated. It will be readily understood how 15 rotation of the mold causes packing of the concrete around the blocks 18 and embeds them in the body of the pole so that they can not be detected in the finished article. The hole 22 which is left in the pole may 20 be used to carry wires 25 from the ground to the top of the pole where they may be attached to wires being carried by the cross arm 13. In the preferred form of construction the hole 26 near the top of the pole 25 through which the wires pass is preferably arranged so as to slant as shown in Fig. 3 thereby preventing water from getting into the pole.

A suitable ornamental cap 30 is provided 30 for the top of the pole, the cap having an extended portion 31 adapted to extend into the upper end of the hole 22 thereby closing the top of the pole and holding the cap 30 properly in place. If it is desired to brace 35 or support the pole by guide wires 32 a metal band 33 can be provided at the top of the pole as shown in the drawings.

The mold in which the pole is cast is of such a configuration as to cause suitable 40 flanges or steps 40 to be formed in the pole at regular intervals as shown in Fig. 1. The steps may be formed along the entire length of the pole although it is preferred that the portion just above the ground be plain as 45 shown in Fig. 1. The upper faces 42 of the flanges 40 are flat and the flanges extend entirely around the pole forming steps as shown in the drawings. The flanges extending entirely around the pole provide 50 steps on all sides of the pole and make it look uniform and sightly. It will be understood however, that the steps do not necessarily have to extend entirely around the pole but may extend only partially around it.

55 In Figs. 4 and 5 other forms of steps are shown which may be advantageously used. In the form of construction shown in Fig. 4 indentations 50 are provided in the pole, in place of projections, so that flat steps 51 are 60 formed. In the form shown in Fig. 5 steps 52 are formed in the pole and the wall of the pole between the steps tapers inwardly and downwardly as clearly shown in the figure.

65 Extending radially from the pole between

the steps there are vertical ribs 60 which form hand holds. The ribs 60 when arranged as shown in Figs. 1 and 2 provide convenient and effective hand holds which a person may grip when climbing the pole. 70 It will be readily understood that the ribs 60 may extend any desired distance from the pole and that there may be any desired number or arrangement of ribs. In the preferred form of the invention the ribs 60 are 75 formed integral with the pole although it will be readily understood that they may be made separate and attached to the pole if so desired.

In Fig. 7 a form of hand hold construction 80 is shown in which indentations 90 are provided in place of projections. This form of construction is very easily embodied in the pole and is very effective.

A form of hand hold construction is 85 shown in Fig. 8 in which both indentations and projections are used. The indentations 90^a are preferably not as deep as the indentations 90 in the form shown in Fig. 7. This form of construction is very ornamental 90 and is at the same time very effective.

In Figs. 9, 10 and 11 a form of construction is shown in which the top or uppermost section 81 of the pole is square or substantially square in cross sectional configuration. 95 In this form of construction recesses 80 are provided in opposite sides of the pole to receive the cross arms 13. The cross arms 13 being carried in the recesses 80 are firmly held in a horizontal position without the aid 100 of brace rods, etc. The recesses being opposite each other as shown in Fig. 10 make it possible to hold the cross bars 13 in place by simple tie bolts 85. In cases where only one cross bar 13 is desired a short block 95 105 of wood or metal can be substituted for one of the cross bars as shown in Fig. 11. The square construction shown at 81 in Figs. 9 and 10 can be used through the entire pole if so desired although it is preferred that it 110 be used only where the cross bars are attached to the pole.

Although I have explained my invention as embodied in a monolithic concrete pole it will be understood that I do not wish to 115 limit myself to such applications as it can be advantageously used in connection with cast metal or wood poles built up or sectional poles. When the invention is used in connection with built up or sectional poles 120 the steps and ribs may be formed integral with the body of the pole or they may be formed separately and afterward attached.

Having described a preferred embodiment of my invention I do not wish to limit 125 myself to the particular details hereinabove set forth but wish to reserve to myself any changes or modifications that may appear to those skilled in the art or fall within the scope of the following claims.

Having described a preferred form of my invention, I claim:

1. A concrete pole having a plurality of integral laterally projecting flanges formed thereon, and a plurality of ribs extending longitudinally thereof between said flanges, for the purpose described.
2. A pole provided with a plurality of annular flanges constituting steps and having a plurality of longitudinally extending grooves formed in its body above each flange to provide hand holds.
3. A tubular pole provided with a plural-

ity of integral annular flanges constituting steps, the body of the pole having a plurality of longitudinally extending grooves formed therein above each flange, and the body immediately above each flange being reduced in diameter. 15

In witness that I claim the foregoing I 20 have hereunto subscribed my name this 18th day of October, 1919.

EDMUND B. BLINN.

Witness:

VIRGINIA BERINGER.
